CARPET.

No. 16,008.

Patented Mar. 31, 1885.

UNITED STATES PATENT OFFICE.

NORIC KOMORI, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 16,008, dated March 31, 1885.

Application filed February 12, 1885. Term of patent 3½ years.

To all whom it may concern:

Be it known that I, NORIC KOMORI, a resident of New York city, in the county and State of New York, have invented and produced, by 5 my own industry, genius, efforts, and expense, a new and original Design for a Carpet, of which the following is a full description, in connection with the accompanying photograph, which represents a face view of my 10 new design for a carpet.

This invention relates to a new ornamentation of the face of a carpet, oil-cloth, or analogous fabric.

In the accompanying photograph are represented the various parts which enter into my 15 new design.

A is a large rosette-like figure, placed near a smaller rosette, B, near which is a trefoil, C, that is connected by a crooked stem with

another rosette, D. Near the rosette B are 20 also fancifully-interlocked stems E.

F is a rosette of peculiar structure, placed at some distance beneath the figure B, and near the figure E is the figure C that is composed of sundry connected rosettes. 25

Somewhat above the figure D are the rosettes H and I, near which is a group of rosettes, J, K, L, and M. Other less prominent figures are also on the background of the carpet.

I claim—

The design for a carpet, the same consisting of the figures A, B, C, D, E, F, G, H, I, J, K, L, and M, substantially as shown. 30

NORIC KOMORI.
